UNITED STATES PATENT OFFICE.

FREDERICK E. KOELLA, OF TOLEDO, OHIO.

FEED MEANS FOR FILM-DISKS.

1,254,239.

Specification of Letters Patent. Patented Jan. 22, 1918.

Application filed September 22, 1916. Serial No. 121,576.

To all whom it may concern:

Be it known that I, FREDERICK E. KOELLA, a citizen of the United States, and a resident of Toledo, in the county of Lucas and State of Ohio, have invented a certain new and useful Feed Means for Film-Disks; and I do hereby declare the following to be a full, clear, and exact description of the invention, such as will enable others skilled in the art to which it appertains to make and use the same, reference being had to the accompanying drawings, and to the characters of reference marked thereon, which form a part of this specification.

This invention relates to moving picture machines both of the projecting and taking type, and particularly to machines of this character employing films of disk form. The primary object of my invention is the provision in a machine of the character described of improved means for imparting intermittent feeding movements to the film to successively move the picture panels in register with the projecting or receiving openings, whereby to enhance the practicability and commercial value of such machines. Further objects and advantages of the invention will be apparent from the following detailed description thereof.

While the invention, in its broader aspect, is capable of embodiment in numerous forms, a preferred embodiment thereof is illustrated in the accompanying drawings, in which—

Figure 1 is a plan view of a machine embodying my invention, with the inclosing case in horizontal section. Fig. 2 is a section thereof on the line 2 in Fig. 1. Fig. 3 is an enlarged perspective view of the film feeding mechanism embodying my invention. Fig. 4 is an enlarged section on the line 4—4 in Fig. 3, and Fig. 5 is an elevation of the film engaging end portion of the feed lever with a part broken away.

Referring to the drawings, 1 designates the case of the machine, in the bottom of which are mounted a pair of spaced parallel rails 2, 2 forming a horizontal track on which the wheels 3 of the carriage 4 are mounted for movement to permit a free horizontal reciprocation of the carriage relative to the case. A shaft 5 is journaled in the carriage 4 transversely thereof and has one end projecting from the carriage and provided with opposed clamping members

6 between which a film disk 7 may be removably clamped to have turning movements with the shaft and transverse movements with the carriage 4.

The picture panels of the film-disk 6 are successively arranged in spiral order on the fact of the disk, as illustrated in Fig. 2, and as well understood in the art. It is therefore evident that when the disk is rotated to either move the pictures thereon in successive order past the projecting opening, when the machine is being used for display purposes, or to bring successive panels into position for receiving an image, when taking pictures, the disk can be moved transversely on its axis at proper speed to allow for the proper arrangement of the picture panels. In other words, the transverse movement of the film must be such as to permit the picture projecting or receiving opening to move radially of the film as it follows the spiral course of the pictures.

In one end of the case 1 is mounted a shaft which carries the operating crank 8 without the case. A train of gears 9 connects the crank-shaft with a shaft 10, which is mounted lengthwise of the case in advance of the path of transverse movements of the film-disk 7 and has one end journaled in a bearing arm 11 projecting from the adjacent case side, and with its other end journaled in a suitable bearing in one end of the case.

The shaft 10 carries a bevel-gear 12 at its inner end in mesh with a larger bevel-gear 13, which is carried by a shaft 14, that is journaled in the upper end of a bearing standard 15 in the horizontal plane of the shaft 10 and at right angles thereto, the gear 13 being disposed at the end of the shaft 14, which is adjacent to the film-disk 7. The standard 15 fixedly rises from the bottom of the case 1 and has its upper end forked, with the shaft 14 extending across the forked opening and journaled in both furcations thereof.

A bearing arm 16 has its inner end loosely mounted on the shaft 14 within the fork opening of the standard 15 for vertical swinging movements relative to said standard, and projects downward and outward from the shaft transversely thereof and in opposition to the shaft 10 and has its outer end terminating in a bearing head 17 having an opening 18 in the side thereof opposed to the film-disk 7. A shaft 19 is jour-

naled in the bearing head 17 lengthwise of its carrying arm and in position to stand in axial register with the shaft 10 when the bearing arm has been swung into suitable 5 position therefor. The shaft 19 carries a bevel-gear 20 on its inner end in mesh with the bevel-gear 13 and of the same size as the gear 12, thus causing like rotation to be communicated to the shaft 19 from the shaft 10 10 through the medium of the gears 12, 13 and 20. A cam-wheel 21 is mounted on the outer end of the shaft 19 and has a protuberant portion 22 on its periphery for the purpose hereinafter described. The shaft 19 has an 15 eccentric portion 23 within the opening 18 in the bearing head 17, and this eccentric portion turns within a yoke 24, that is carried at the inner end of a stub-shaft 25, which projects horizontally toward the film-disk 7 through a registering bearing in a 20 side wall of the bearing head 17, as best shown in Figs. 3 and 4.

A film feeding lever 26 is mounted on the outer end portion of the stub-shaft 25 for 25 rocking movements relative thereto and has its film engaging arm projecting horizontally to a point between the gear 13 and the film-disk 7 and provided at its outer end with a transversely projecting finger 27, 30 the outer end of which is socketed to receive a film engaging member 28 of rubber or other suitable material for frictionally engaging the film side and imparting feeding movements thereto as the feed arm is successively rocked, as hereinafter described. A coiled compression spring 29 encircles the stub-shaft 25 between the bearing head 17 and lever 26 and acts to normally urge an outward movement of the lever 26 toward 35 the film 7. At each revolution of the shaft 19, the eccentric 23 causes the shaft 25 and lever 26 to be drawn inward to film releasing position and then permits an outward film engaging movement of the lever under 40 the influence of the spring 29. The tail-end 26^a of the lever 26 terminates over the cam-wheel 21 and carries a roller 30 in position to be engaged by the protuberant part 22 of the cam-wheel at each revolution thereof.

45 A coiled contractile spring 31 connects the tail-piece of the lever to the head 17 and normally retains the lever with its rear end or tail-piece 26^a lowered in stop contact with an adjusting screw 32, which threads up 50 through the outer end portion of the bearing head 17 and is adjustable to vary the normal position of the lever with respect to the cam-wheel 21. At each revolution of the cam-wheel, the peripheral projection 22 55 thereon engages the lever roller 30 and imparts a film feeding movement to the lever 26 against the tension of the spring 31. The engagement of the cam projection 22 with the lever roller 30 is so timed with respect 60 to the reciprocatory movements of the lever 65

carrying shaft 25 that the working end of the lever 26 has a downward film feeding movement imparted thereto when the lever is at the limit of its outward movement with respect to the bearing head 17, or in other words, when the film wiping member 28 of the lever is in engagement with the film, thus causing a normal feeding movement to be imparted to the film-disk by the downward wiping action of the feed member 28 70 thereagainst.

A segmental rack-bar 33 is pivoted at its upper end to a side of the bearing head 17 at its outer end, as by a screw 34, and projects downward and inward through the 80 lower portion of the standard 15 and has its rack-teeth, which are provided on the upper surface thereof, in mesh with a pinion 35, which pinion is mounted on a shaft 36, that is journaled in the standard 15 and 85 has one end projecting outward therefrom through a side of the case 1 and carrying a hand-wheel 37 at its outer end. It is evident that a turning of the shaft 36 and pinion 35 will impart longitudinal movement 90 in one direction or the other to the rack-bar 33 and a corresponding raising or lowering of the bearing head 17 with respect to the shaft 14 as an axis.

It will be noted by reference to Fig. 2 95 that the shaft 19 and the operating arm of the lever 26, which is in a horizontal plane therewith, are disposed slightly out of radial alinement with the film-disk axis, or in tangential relation to a circle concentric to 100 said axis so that the feed lever, when swung downward in film feeding direction, will have a movement which is concentric to the film axis and which, in addition to imparting a turning movement to the film, also 105 draws the film and its feeding carriage 4 slightly to the right to compensate for the spiral arrangement of the picture panels.

It is evident that the speed of transverse movement of the film-disk depends on the 110 inclination of the lever 26 with respect to the plane of transverse movement of the film axis and that an adjustment of the bearing arm 16 and parts carried thereby is effected for this purpose by a turning of the 115 shaft 36 and pinion 35.

The film-disk 7 is pressed or held firm in opposition to the point of engagement of the same by the feed lever 26 by a pressure pad 38, which is carried at the free end of 120 an arm 39, that projects from a shaft 40, which shaft is suitably journaled in vertical position within the adjacent end portion of the case. A coiled contractile spring 41 connects a tail-piece 42 on the arm 39 to an 125 adjacent portion of the case 1 and acts on said arm to retain the pad 38 in yielding contact with the rear side of the film. The film pressing movement of the pad 38 is limited, however, by a stop-pin 43, which is 130

positioned to have stop contact with the tail-piece 42, as shown in Fig. 1. The picture image is transmitted to the film or projected from the same through an opening 44 in the pad 38, said opening being properly positioned and of suitable size for the picture panels in the film to successively move into register therewith as the film is rotated. When the film-disk 7 is at rest, it is firmly held to the pad 38 by a pressure-foot 45, which is carried at the outer end of one arm of a bell-crank lever 46 and has an opening 47 therein in register with the opening 44 in said pad. The lever 46 is fulcrumed to a bearing arm 48 projecting from the adjacent case end and has one arm projecting at the outer side of a cam-disk 49 on the shaft 10 in position to be engaged and rocked by a cam projection 50 on the adjacent cam face at each revolution of said shaft. A coiled contractile spring 51 connects the lever 46 to a stationary plate or member 52 within the case and acts to normally move the lever 46 to retain its pressure-foot 45 in contact with the film and its other arm in the path of movement of the cam projection 50. As the cam projection 50 strikes the lever 46, the lever is rocked to release the engagement of the pressure-foot 45 with the film and this releasing movement is timed to take place immediately prior to the film feeding movement of the feed lever 26, the pressure-foot being held outward from the film during such feeding movement.

In the present instance, the large bevel-gear 13, in addition to serving as a driving connection between the gears 12 and 20, is utilized as the shutter member of the machine and for such purpose is provided with two openings 53 in its web portion at opposite sides of its center, which openings are successively brought into register with the openings 44 and 47 in the pad 38 and pressure-foot 45, respectively. The gear 13 is of suitable size with respect to the gears 12 and 20 to turn once for every two revolutions of said other gears so that one of the openings 53 is brought into register with the projecting openings of the machine during each half revolution of the shutter gear.

The member 52 above referred to, in the present instance, constitutes a light protective plate which is disposed between the shutter gear 13 and the film and is provided with an opening therethrough in register with the line of transmission of the picture images.

In the use of my improved machine, a film-disk 7 is first clamped to the shaft 5 and the carriage moved to the left in position for the last picture panel in the outer convolution of the series to move into register with the picture projecting openings

when the film is rotated in feeding direction. Upon a turning of the operating crank 8, a rapid rotation is communicated to the shaft 19 from the shaft 10 through the medium of the gears 12, 13 and 20, thereby causing the eccentric 23 in conjunction with the spring 29 to impart both an inward and outward movement to the feed lever 26 with respect to the film-disk 7 at each revolution of the shaft 19 and also to cause the cam-wheel projection 22 to act on the outer end of the feed lever 26 to impart a quick downward rocking or film feeding movement to the opposite end thereof against the tension of the spring 31, which feeding movement takes place during the period that the lever is held upward by the eccentric 23 with its wiper member 28 in contact with the film. It is therefore evident that the lever 26 has compound movements imparted thereto at each revolution of the shaft 19, which movements coöperate to move the lever into film engaging position, to then impart a feeding or turning movement to the film whereby a succeeding picture panel thereon is moved into projecting position, and then to retract the lever from film engaging position. The setting of the rocking axis of the lever 26 below the horizontal plane in which the film axis and the lever wiper member 28, when elevated, are disposed, causes the downward wiping or feeding action of the member 28 on the film to impart not only a rotary feeding movement to the film but to draw it slightly forward or to the right to allow for the gradual inward working of the film panels toward the center of the film due to the spiral arrangement of such panels. It is evident that as the convolutions of the picture panels become shorter or of less diameter, the forward feeding of the film must be correspondingly increased and this, in the present instance, is accomplished by the operator slightly turning the control shaft 110 37 at frequent intervals so as to increase the incline of the feed finger. At each downward rocking or feeding movement of the lever 26, the pressure-foot lever 45 is swung outward from engagement with the film by the coaction of the cam projection 50 with the lever 46. In order to facilitate an insertion of a film-disk 7 between the pressure-pad 38 and pressure-foot 45, the shaft 40, which carries the pressure-pad arm 39, is projected without the case 1 and carries a hand-control wheel 54, thus enabling the operator to turn said shaft and swing the pressure-pad 38 outward away from the film against the tension of the spring 41 when desired.

I wish it understood that my invention is not limited to any specific construction, arrangement or form of the parts, as it is capable of numerous modifications and varia-

tions in the different parts without departing from the scope of the invention as defined in the claims.

Having thus described my invention, 5 what I claim as new, and desire to secure by Letters Patent, is—

1. The combination with a rotatable film-disk, of a film engaging member, and mechanism for operating said member to impart 10 periodical frictional film wiping movements thereto.

2. The combination with a rotatable film-disk, of a film engaging member, and mechanism operable to periodically move said 15 member into and out of film engaging position and to impart an oscillatory film turning movement thereto when in film engaging position, with the axis of such oscillating movement substantially parallel to the 20 film axis.

3. The combination with a rotatable film-disk, of a feed lever having a film engaging 25 part projecting transversely therefrom, said lever being mounted at one side of the film, and mechanism operable to periodically move the lever axially of its fulcrum to place the film engaging part thereof into and out of film engaging position and to rock said lever when in film engaging position to impart a rotary movement to the 30 film.

4. The combination with a rotatable disk-like member, of a feed lever mounted at one 35 side of said member for movements longitudinal and transverse to its rocking axis with respect thereto, and mechanism operable to move said lever in one direction into and out of member engaging position and to move the lever in a different direction when 40 in member engaging position to impart rotary movement to said member.

5. The combination with a rotatable disk-like member, of a feed lever mounted at one 45 side of said member for movements in different directions with respect thereto, mechanism operable to move said lever in one direction into and out of member engaging position and to move the lever in a different direction when in member engaging position 50 to impart rotary movement to said member, and means for adjusting the film feeding stroke of the lever.

6. The combination with a rotatable disk, of a movable feed member therefor disposed 55 at one side thereof, and mechanism periodically operable first to move said feed member longitudinally of its axis into contact with the disk, then to oscillate the member to impart predetermined rotary movement 60 to the disk, then to move the member away from the disk and impart a return rocking movement thereto.

7. The combination with a rotatable disk, of a lever mounted at one side of said disk 65 for rocking movements transversely of the

disk axis and for axial shifting movements toward and away from the disk, means normally retaining the lever in one position of its rocking movement, and mechanism operable to periodically move the lever toward 70 and away from the disk to engage and release the same and operable to rock the lever from normal position when in engagement with the disk to impart rotary movement thereto. 75

8. The combination with a rotatable disk, of mechanism having a disk wiping member and operable to periodically move said member to impart rotary movement to the disk, and means for gripping the disk and automatically operable to release the same during a disk feeding movement of said mechanism. 80

9. The combination with a rotatable disk, of means operable to grip said disk and to 85 periodically release the same, and mechanism having a lever member operable to periodically engage and impart rotary movements to said disk when released by said means. 90

10. The combination with a rotary disk, of a pressure member disposed at one side of said disk, means operable to clamp the disk to said pressure member and to periodically release the same, and mechanism operable to periodically move a part thereof into engagement with the disk in opposition to said pressure member and to impart predetermined rotary movement to the disk when released by said means. 95

11. The combination with a disk mounted for rotary and transverse movements, of mechanism operable to periodically impart simultaneous rotary and transverse movements to said disk, and means for adjusting 105 said mechanism to vary the extent of film movements. 100

12. The combination with a disk mounted for rotary and transverse movements, of a feed lever mounted at one side of said disk, 110 and means operable to periodically move said lever axially of its fulcrum into and out of disk engaging position and to rock the lever when in engagement with the disk to impart both rotary and transverse movements 115 thereto.

13. The combination with a disk mounted for rotary and transverse movements, of a feed member mounted at one side of said disk for different movements with respect 120 thereto, mechanism operable to periodically move said member into and out of engagement with the disk and to have a swinging movement in engagement with the disk eccentric to its axis to impart both rotary and 125 transverse movements to said disk.

14. The combination with a disk mounted for rotary and transverse movements, of mechanism operable to periodically engage 130 said disk and to impart simultaneous rotary

and transverse movements thereto, and means for adjusting said mechanism to vary the extent of transverse moving of the disk by said mechanism at each feeding operation 5 thereof.

15. The combination with a film-disk mounted for rotary and transverse movements, of an arm mounted at one side of said disk for swinging movements in a plane 10 parallel with the disk surface, means carried by said arm and operable to periodically engage the disk and to impart combined rotary and transverse movements thereto, means for adjusting said arm to vary the 15 position of the feeding means with respect to the disk whereby the extent of transverse feeding of the disk at each feeding operation may be increased or diminished, and means for operating said feeding means at 20 any position of adjustment thereof.

16. In a moving picture machine, a film mounted for rotary movements and for movements transverse to its axis, a member mounted for rocking movements in a plane

substantially parallel to the plane of rotation of the film and adapted when rocked to have wiping engagement with the film to rotate the same, the rocking axis of said member being offset from the axis of rotation of said film whereby the rocking movement of said member is eccentric to the film axis and adapted to impart transverse movement to the film. 25 30

17. In a moving picture machine, a film mounted for rotary and substantially horizontal transverse movements relative to its axis, a film feeding member disposed in reclining position at a side of said film in tangential relation to the film axis and mounted for vertical rocking movements 40 with its rocking axis intersecting the plane of rotation of the film, and means for rocking said member to periodically engage the film and impart predetermined rotating and 45 transverse movements thereto. 45

In testimony whereof, I have hereunto signed my name to this specification.

FREDERICK E. KOELLA.
